ABSTRACT: A variable resistor providing an integral assembly for dual operation comprising a pair of arcuate resistance track elements in axially spaced, face-to-face relationship and having interposed therebetween a single insulating rotor or brush carrier including oppositely facing cavities, each cavity being recessed relative to a central plane and adapted to individually receive conducting brush members. Biasing springs are provided for maintaining the brush members in electrical contact with the respective resistance elements, as well as individual terminal assemblies for each of the resistance elements.

ATTORNEY

VARIABLE RESISTOR FOR DUAL OPERATION

BACKGROUND OF THE INVENTION

The present invention relates to mechanically variable resistors having movable contacts electrically adjustable over a length of resistance element, and in particular to a variable resistor wherein there is a pair of such resistance elements in axially spaced, facing relationship and including respective movable contacts for each of the elements actuated by a single rotor, and in which all of the components are enclosed in a single housing.

Components of the nature disclosed herein have in the past been mounted in tandem arrangement with individual movable contact elements electrically engaging separate resistance elements. The movable contact elements were attached in axially spaced relationship along a common operating shaft. This made for relatively long and cumbersome constructions. There have also been some attempts to combine the contacts in a single rotor, but these contacts were generally of leaf spring construction with the contact buttons being made an integral part of the distal end of the lead spring and very much dependent upon variations in the spring material, length of spring and other factors influencing the tolerance of the construction.

SUMMARY OF THE INVENTION

The present invention contemplates, in its preferred embodiment, the provision of a variable resistor which is diminutive in size, and therefore very suitable for use on printed circuit boards including a multiplicity of electronic components. In this age when users of printed circuit boards and other electronic gear are striving to miniaturize such components, it is essential that variable resistance devices conform to such practice. There has been provided by the present invention a device that will readily adapt itself to such applications as bridged T- and L-attenuators which require in their construction the obtainment of a specified resistance impedance in the operation of dual variable resistance. It is further important that the impedance relationship be maintained throughout the range of resistance values as the device is operated. The manner of construction of the present device provides a positive attainment of such impedance relationship, independent of the variations normally found in leaf spring contact constructions.

The present invention, in its preferred embodiment, adapts certain of the features of the Variable Resistance Device disclosed in U.S. Pat. No. 2,839,642 granted to the present inventor jointly with Bernard F. Tellkamp and assigned to the same assignee as the present invention. That is, the embodiment may utilize integrally molded resistor elements such as those set forth in the U.S. Pat. Nos. 2,269,136 and 2,514,682 to Tellkamp. However, it is contemplated that the construction of tee resistance elements may take other forms such as conventional cermet or thick film resistance tracks, as well as other resistance tracks well known in the art.

The resistance elements each provide an arcuate track which may be of constant resistance throughout its length or variable, as desired, and in the case of potentiometers, a centrally disposed collector track of conducting, low-resistance material. The resistance elements are retained in axially spaced, face-to-face relationship by means of a tubular enclosure or casing. An operating shaft protrudes through a central aperture of one of the resistance elements and has attached to its internal end portion an insulating rotor element including two oppositely disposed cavities recessed inwardly relative to a central plane dividing the rotor perpendicularly of its axis. Within each of the cavities there is located a conducting brush which is rotatable with the rotor about an axis substantially concentric with the respective resistance tracks and having collector engaging portions in sliding contact with the collector track and a resistance engaging portion in sliding contact with the resistance track. Relatively flat spring elements are seated in the respective cavities to bias the brushes outwardly

of the cavities and towards their respective resistance elements.

It is therefore among the objects of the present invention to provide a variable resistor of diminutive size which includes among its various features the provision of well proven and commercially accepted resistance elements and brush constructions and which combine all of these features in the device to provide a dual functioning, variable resistor enclosed within a single housing to thereby reduce both its radial and axial length when compared to conventional tandem operated variable resistors.

BRIEF DESCRIPTION OF THE DRAWING

15 The attached drawing, which comprises a part hereof, discloses the invention, as follows:

FIG. 1 is a longitudinal view, partially in section, of a variable resistor in the form of a potentiometer incorporating the teachings of the present invention;

20 FIG. 2 is a cross-sectional view taken along lines 2-2 of FIG. 1 and illustrating, more particularly, a construction of the rotor or brush carrier;

25 FIG. 3 is a cross-sectional view taken along lines 3-3 of FIG. 1, and illustrates the configuration of the resistance track and collector track as used in the dual resistance elements; and

FIG. 4 is an enlarged fragmentary view of another embodiment of the brush construction.

DESCRIPTION OF THE PREFERRED EMBODIMENTS

30 Referring now to the drawing, and in particular to the views of FIGS. 1-3, there is shown a resistance element in the form of a molded base 10 of insulating material. The base 10 provides a surface 11 preferably of circular configuration. The configuration of the resistance and collector tracks of the surface 11 is similar to the interior surface 12 of an axially spaced resistance element 13, except for a rotative positioning relative to the longitudinal plane of the device for purposes hereinafter described. Attention is directed to FIG. 3 which

35 more clearly shows the configuration of the surface 12 of the element 13. Embedded within the base 10 and the element 13, and exposed flush with the respective faces 11 and 12, are circular resistance tracks 14 and 15, respectively, each in the form of a nearly completed ring. The tracks 14,15 each comprise a shallow layer of conducting material in the form of distributed carbon black particles dispersed within the molded material of the respective base 10 and element 13 to have become an integral portion thereof upon molding. Substantially concentric with the resistance tracks 14, 15 are respective collector tracks 16 and 17, also exposed flush with the respective faces 11 and 12. The tracks 16, 17 cover a circular area at the center of the respective faces 11 and 12 and, like the tracks 14, 15 are formed of a plurality of conducting particles molded integrally with the respective base 10 and element 13 in a shallow layer near the surface. The particles comprising the collector tracks 16, 17 are more densely distributed than in the resistance tracks 14, 15 to provide a conducting spot area of relatively small resistance. Variable resistance apparatus comprising resistance in collector tracks of conducting materials molded within a base of insulating material, such as herein described, are known as integrally molded resistors of which certain forms have been set forth and described in the U.S. Pat. Nos. 2,269,136 and 2,514,682 to Tellkamp.

40 45 50 55 60 65 70 75

Referring to the description of the base 10, a set of three-terminal leads 20 (one of them not being shown) are embedded within the base 10 at the time of molding and there disposed with the embedded end of one in electrical contact with the collector track 16 and the embedded ends of the others in contact with the end portions of the resistance track

It is also within the province of the present invention to provide resistance and collector tracks, or merely resistance tracks when the device takes the form of a resistance device only rather than a potentiometer, in the form of thick film or cermet surfaces as is well known in the art.

Returning to the description of the base 10, a set of three-terminal leads 20 (one of them not being shown) are embedded within the base 10 at the time of molding and there disposed with the embedded end of one in electrical contact with the collector track 16 and the embedded ends of the others in contact with the end portions of the resistance track

14. The terminals 20 are shown in longitudinal projection from the base 10 relative to the view of FIG. 1. If it is desired to provide terminals which project downwardly relative to FIG. 1, a portion of the projecting ends of the terminals 20 may be clipped and soldered or welded to a printed circuit plate (not shown) having its own downwardly projecting terminals in accordance with conventional practice.

The terminals 21 of the element 13 are molded in place in similar manner to terminals 20, and project downwardly relative to FIG. 1. Should it be desired to provide the aforementioned means for including downwardly projecting terminals 20, the sets of terminals 20, 21 will be chosen dimensionally to fit into known circuit board constructions.

Both the molded base 10 and the resistance element 13 also have embedded therein metallic heat extracting and housing anchoring inserts 22 and 23, preferably composed of a metal having high heat conductivity. The inserts are more clearly shown and described in detail in the Dickinson et al. U.S. Pat. No. 2,839,642. They generally take the form of an interrupted cylinder with a plurality of perforations through which the material of the base 10 and the element 13 may flow, upon molding, to rigidly secure the inserts 22, 23. Each of the inserts 22, 23 with its respective forward edge 24, 25 behind, spaced from but very near the respective resistance tracks 14, 15, as shown in FIG. 1, to readily receive heat released within the resistance tracks 14, 15 and to conduct the same to the exterior of the base 10 and resistance element 13.

The base 10 and resistance element 13 are retained in axially spaced relationship by means of a housing or casing 26 which is preferably of a metallic heat-conducting material. At the bottom of the housing, as viewed in FIG. 1, it will be noted that a portion of the housing is lanced inwardly from its right end with the separated portion bent inwardly to form a rotor stop as will be later described. The casing 26 is provided with a set of ears (not shown) which act to retain a threaded bushing 30 having a circular base 31 resting against the resistance element 13. The free ends of the aforementioned ears are bent over the bushing base 31 to secure the bushing 30 in position. Extending through the bushing 30 is an operating shaft 32 having a reduced cross section 33 and a knurled end 34 within the casing 26. The knurled end 34 and the reduced portion 33 are embedded within a molded contact carrier or rotor 35 composed of an insulating material. The rotor is provided with a projecting molded portion 39 which acts to insulate the shaft 32 from the collector ring 17 in addition to providing a bearing surface for the rotor 35.

The bushing 30 is recessed at 36 to receive an O-ring gasket 37 which is compressed between the interior circular wall of the recessed cavity 36 and the shaft 32 to provide a seal.

The brush carrier or rotor 35 is slotted at 38 for purposes of assembly in order to clear the inwardly folded portion 27 of the casing. Although not shown, the rotor 35 is molded to provide a projection which will engage either side of the portion 27 for purposes of limiting rotation thereof. The movement of the brushes, which will later be described, is thus confined to within the limits of the respective resistance tracks 14 and 15.

Although the operation of the individual potentiometers of the device illustrated are similar to those of the Dickinson U.S. Pat. No. 2,839,642, it will be appreciated that the present invention contemplates a combination of these features in a form which will provide dual function in a single unit because of a novel modification of the brush carrier or rotor 35 to permit this dual function. That is, the brush carrier 35 is recessed to provide diametrically opposed cavities 40 for respectively receiving electrically conducting brushes 42 and 43 of carbon and the respective pair of biased springs 44 and 45. With reference to FIGS. 1 and 2, it will be noted that each of the brushes has a substantially identical configuration, the rearward side of brush 43 and the forward side of brush 42 being shown in the cross-sectional view of FIG. 2. As viewed in FIG. 1 and 2, it will be noted that the brush carrier 35 is provided with an arcuate protruding portion 46 which acts as a stop for the rotor 35 on any endward, axial thrust being placed upon

the shaft 32 during adjustment. That is, the rotor 35 will in no way touch the resistance track 15 or the collector track 17 as the protruding portion 46 is disposed to rest against the inner face 11 of the base 10 intermediate the said tracks 15 and 17.

5 Each of the brushes 42, 43 are of general triangular configuration to be respectively seated in the generally triangular configured recesses 40 and 41 of the rotor 35, respectively. As shown in FIG. 2 and as particularly illustrated with regard to brush 42, each of the brushes 42, 43 are provided with three 10 contact toes 47, 48 and 49. The two radially inwardly disposed toes 48, 49 rest upon and electrically engage the respective collector tracks 10 and 17 of the base 10 and the resistance element 13, whereas the outwardly positioned toe 47 rides upon and electrically engages the resistance tracks 14 and 15. 15 The triangular disposition and spacing of the toes 47, 48 and 49 also provides stability for the respective brushes 42, 43.

As shown on FIG. 2, the springs 44, 45 are disposed in laterally projecting recessed portions of the cavities 40 and 41. The laterally projecting recesses are formed with abutments at their extremities 50 to receive the ends of the respective springs 44, 45. The intermediate portion of each of the springs 44, 45 bears against the angled back surface 51 of the respective brushes 42, 43 and is bowed to provide necessary contact pressure between the brush toes 47 and the exposed surface areas of the tracks 14, 15 and 16, 17. It will be further observed that the force exerted by the springs 44, 45 against the angled back surface 51 divides into two components, one biasing the respective brush 42, 43 towards the respective faces 11 and 12, and the other force component biasing the respective brush in a direction towards the forward surface defining the toe 47. The latter component acts to retain the brush in its cavity, which is especially helpful during assembly of the device. The use of a plurality of springs 44, 45 permits contacting engagement with the angled back surface 51 of the brush to provide a spring characteristic similar to that of a flat spring.

It will be apparent from the above description that manual rotation of the shaft 32 will cause the rotor 35 molded to the inward end of the shaft to rotationally move the conducting brushes 42 and 43 circumferentially of the concentric resistance and collector tracks 14, 16 and 15, 17, respectively. This dual operation is performed in a minimum axial dimension between the resistance elements 10 and 13 by seating the respective brushes 42 and 43 in cavities 40 and 41 which are disposed inwardly of a plane cross-sectionally bisecting the rotor.

FIG. 4 is illustrative of another brush embodiment, and like parts are described by referring to like numerals. As stated above, the springs 44, 45 bear against the angled back surface 51 of the brushes 42, 43. This arrangement provides desired contact pressure between the toe 47 and the respective resistor track 14, 15. However, such arrangement also tends to wedge the apex forming the outer surface of the toe 47 of the triangular brush against the mating surface of the triangular recess of the rotor 35.

In order to minimize the wedging condition and thereby permit freedom of brush action when the rotor is operated, the surface of the recess engaging the toe 47 is preferably formed as shown in FIG. 4. That is, the apex is further defined by the planar surface portions 52 and 53, which lie in angular planes intersecting at the terminus of the apex. This provides a "two point" contact for the rounded toe 47. The brush 43 (shown in FIG. 4) and the brush 42 will then be assured freedom of movement in the recess 41 of the rotor 35 even under bias of the respective springs 45, 44.

I claim:

1. A variable resistance apparatus comprising:
a housing;
a pair of spaced-apart, stationary insulating substrate elements supported by said housing, at least one of which includes a shaft-receiving aperture;
an arcuate resistance track and a conducting collector track supported by each of said substrate elements and in respective facing relationship;

a rotatable shaft received in the apertured substrate element and extending inwardly of said housing; an integrally formed insulated contact brush carrier supported on the inner end of said rotatable shaft and positioned intermediate said resistance elements, said contact brush carrier containing a pair of reentrant brush-receiving cavities on opposite sides thereof and disposed angularly relative to one another, the open ends of said cavities facing respective resistance tracks and collector tracks supported by the respective substrate elements, the 10 said reentrant cavities of said brush carrier each having a depth exceeding one-half the axial length of said brush carrier;

conducting contact brushes disposed on opposite sides of 15 said contact carrier and positioned in the respective cavities of said contact brush carrier and slidably electrically bridging the respective facing resistance and collector tracks;

biasing means at opposite sides of said contact carrier disposed in said respective cavities intermediate a respective inner end of said cavities and its respective brush, thereby biasing said brush into electrical bridging engagement with said resistance track and said conducting collector track supported by the respective substrate elements; and 20

terminal connections for said respective resistance tracks and said respective collector tracks.

2. The variable resistance apparatus of claim 1, wherein said respective brushes are of triangular configuration and include three protruding toes each being located at the respective 30 apices of each of said brushes, one of said toes being in sliding electrical contact with said arcuate resistance track and the remaining toes being in sliding electrical contact with said collector track.

3. The variable resistance apparatus of claim 1, wherein 35 each of the brush-receiving cavities are triangularly shaped and disposed with an apex positioned for rotational alignment with its respective arcuate resistance track and said one apex being further configured at its terminus to define planar wall surfaces lying in angular intersecting planes, said wall surfaces being normal to said respective resistance track, and said respective brushes being triangularly shaped and seated in a respective cavity with one apex being arcuately configured and in linear engagement with each of the respective said planar wall surfaces of said one apex of said cavity.

4. The variable resistance apparatus of claim 1, wherein the distal end surface of the shaft-supported brush carrier includes a protruding portion spaced from said arcuate resistance track to prevent the said end surface from wiping against said track during rotation of said shaft.

5. The variable resistance apparatus of claim 3, wherein the inner back surface of each of the respective brushes is angularly disposed relative to the plane intersecting the end of said brushes in electrically bridging engagement with said tracks, and wherein the biasing means comprises an elongated spring disposed transversely of and pressing against said angularly disposed back surface to provide a resultant force acting to concurrently force the respective brush in a direction into engagement with its respective resistance track and to force said arcuately formed apex of said brush into said linear engagement with said planar wall surfaces of said cavity.

6. In a variable resistance apparatus comprising:

a housing;
a stationary insulating substrate element supported by said housing and including an interiorly facing surface supporting an arcuate resistance track and a conducting collector track;

a rotatable shaft extending inwardly of said housing and supporting at its inner end a contact brush carrier; the combination therewith of;

triangularly shaped, brush-receiving cavities in said brush carrier and disposed with one apex thereof positioned for rotational alignment with the said arcuate resistance track, and said one apex being further configured at its terminus to define planar wall surfaces lying in angular intersecting planes, said wall surfaces being substantially normal to the surface of said substrate element supporting said resistance track;

a conducting brush seated in said cavity and having an exposed surface in slidably electrically bridging engagement with said tracks, said brush being triangularly shaped with one apex being arcuately configured and in linear engagement with each of the respective planar wall surfaces of said one apex of said cavity; and

biasing means disposed in said cavity intermediate the inner end of said cavity and said brush, to thereby bias said brush into electrical bridging engagement with said tracks.

7. In the variable resistance apparatus of claim 6, the inner

40 back surface of said brush being angularly disposed relative to the plane intersecting the end of said brush in electrically bridging engagement with said tracks, and wherein the said biasing means comprises an elongated spring disposed transversely of and pressing against said angularly disposed back 45 surface of said brush to provide a resultant force acting to concurrently force the brush in a direction towards engagement with said tracks and to force said arcuately formed apex of said brush into said linear engagement with said planar wall surface of said cavity.
